UNITED STATES PATENT OFFICE

BYRON T. MOTTINGER, OF YOUNGSTOWN, OHIO.

ELECTROMAGNETIC SEPARATOR.

1,093,875.

Specification of Letters Patent. Patented Apr. 21, 1914.

Application filed August 4, 1913. Serial No. 732,860.

To all whom it may concern:

Be it known that I, BYRON T. MOTTINGER, residing at Youngstown, in the county of Mahoning and State of Ohio, have invented 5 certain new and useful Improvements in Electromagnetic Separators, of which the following is a specification.

My invention is an improved apparatus for separating magnetic material from pot- 10 ters' sand, clay, slip, grain, seed, flour, etc.

The invention primarily has for its ob- 15 ject to provide a simple, inexpensive device for the purpose, which is self-regulating, easily cleaned and one which can be manu- 20 factured at a low cost.

Generically, the invention provides an 25 electromagnet having a passage through the same, bridged by plates which have ap- 30 pertures or passageways extending in the direc- 35 tion of the lines of force, the plates being, in effect, the poles of the magnet. The ma- 40 terial to be separated is passed through the openings in the pole plates parallel to the direction of the lines of force, thereby in- 45 creasing the effectiveness and efficiency of the apparatus.

Heretofore it has been the practice, in 50 those separators now in use with which I am familiar, to pass the material through the magnetic field at right angles to the 55 lines of force. In such type of apparatus, it has been found that the iron will accumu- 60 late at the edge of the perimeter of the poles and on one side only, bridge the air 65 gap, which in turn strengthens the field at 70 this place, and very rapidly reduces the air 75 gap, and chokes up the apparatus.

It is one of the objects of my invention 80 to avoid this objection.

More in detail, the invention includes 85 those novel features of construction, combi- 90 nation and arrangement of parts, all of 95 which will be first fully described, then be specifically pointed out in the appended 100 claims, reference being had to the accom- 105 panying drawings, in which:

Figure 1 is a central vertical longitudinal 110 section of one form of the apparatus. Fig. 115 2 is a top plan view of the same. Fig. 3 is 120 a central horizontal section on the line 3—3 125 of Fig. 1. Fig. 4 is a central vertical longitudinal section of a modification adapted for 130 the separation of magnetic material from 135 slip or other fluid substances. Fig. 5 is a 140 top plan view of another modification of 145 the apparatus, the same being made of rec-

tangular shape of laminated material. Fig. 15 6 is an enlarged detail plan view of a por- 16 tion of the apparatus shown in Fig. 5, and 17 illustrating the laminee of the pole plates. 18 Fig. 7 is a detail view of a further modifi- 19 cation hereinafter specifically referred to. 20 Fig. 8 is a detail sectional view of a further 21 modification.

By reference to the accompanying draw- 22 ings, in which like numerals and letters of 23 reference indicate like parts in all of the 24 figures, it will be seen that 1 designates the 25 magnet field which is of the iron-clad type, 26 and is composed of an upper half 6 and a 27 lower half 2, each section including an annular 28 wire pocket 3 to receive the magnet 29 wire, a central passage 18 and beveled pole 30 ends 4 adjacent to the inside of the field. 31 Each section of the magnet also has a base 32 flange 5 and the two sections are fastened 33 together by bolts 7, or otherwise. Each of 34 the magnet sections 2 and 6 has an inner 35 annular section 8 to receive the pole plates 36 11 and 14 respectively which bridge the 37 central passage 18 of the apparatus. Each 38 pole plate 11 and 14 has holes 12 and 15 39 respectively bored through parallel to the 40 axis of the passage 18 and to the magnetic 41 lines of force. 42

13 is the air gap which may be of uniform 43 length throughout, or by making the oppo- 44 sing faces of the plates 11 and 14 slightly 45 coniform, as shown in Fig. 7, to lengthen 46 the air gap at the perimeter, the reluctance 47 of the path to the center of the plate will 48 be equalized.

16 is a brass or other non-magnetic ring, 49 suitably packed at 17 to keep the metallic 50 particles out of the space between the be- 51 valed surfaces 4 and out of the wire chamber.

When the apparatus is to be used with 52 dry materials, such as sand, flour, grain, 53 seed, etc., the foregoing described parts are 54 all that are essentially necessary, the mate- 55 rial being discharged into the upper end of 56 the passage 18 and gravitating through such 57 passage, the non-magnetic material passing 58 through the pole plates and being discharged 59 at the lower end of the passage, while the 60 magnetic material is separated out at the 61 pole plates and clings to the walls of the 62 bores of the plates. As the magnetic mate- 63 rial clogs up the pole plate bores or pas- 64 sages, the flow is proportionately diminished 65 and finally stopped. In order to remove the 66 magnetic material, the current is shut off.

from the magnet, the top plate 14 removed and the bottom portion is cleaned by blowing with compressed air. The iron contained in a car load of sand, for example, does not exceed probably one pound, so the cleaning out is not considered a disadvantage.

When the apparatus is to be employed in handling slip, (slip is potters' clay after it has been ground, mixed with water and run through a 126-mesh sieve, the material having the consistency of cream), the form shown in Fig. 4 is employed, and in this form, the bottom of the passage 18 is closed by a plate 19 which carries a three-way valve 20, one way of which is connected to a waste pipe 21, while another way is connected to a pipe 22 from the slip storage tank. The top of the passage 18 is also closed by a spout 24, whose flange 23 is bolted or otherwise secured to the base flange 5 of the upper magnet section 6. In using this form, the slip is forced upwardly by hydrostatic pressure through the passage 18, the magnetic particles accumulating at the poles 11-14, while the slip passes out of the spout until the pole plates become clogged with magnetic material, whereupon the flow automatically ceases. The valve 20 is then closed to the pipe 22 and opened to the pipe 21, the current is shut off, the top plate 14 and spout 24 removed, and a bucket of water is dashed into the top of the passageway 18 to remove the iron which is washed out into the waste pipe 21.

If desired, the magnetic field and pole plates may be built up in rectangular form of laminated material as, for example, the one indicated in Figs. 5 and 6, the corners 40 being solid and the laminae 26 of the field being bolted or otherwise secured to the corners. The pole plates may be made of laminae 27 spaced apart, as shown at 28, to form the passageways.

45 In Fig. 8, is illustrated a modified form of the pole plate construction. In this construction the alternate holes 15-12 in the said plates are bored slightly larger than the other holes and into the smaller holes 50 pins 29 are tightly set, as clearly shown in the said Fig. 8. It will be noticed by referring to said Fig. 8, that the pins of the opposing plates project into the larger holes of the opposing plates. In this form, the 55 openings in the opposing plates are relatively staggeredly arranged and this arrangement I have found to be of advantage in separating metallic particles from certain substances.

60 From the foregoing description taken in connection with the accompanying drawings, the complete construction, operation and advantages of the invention will, it is believed, be clear to those skilled in the art, and I desire to say that slight changes in

the details of construction and arrangement of parts may be made without departing from the spirit of the invention.

What I claim is:

1. A field magnet having a passageway through the same adapted for the passage of the material to be separated, pole plates bridging such passageway and spaced apart to form an interpolar gap, said plates having bores extending through the same in the direction of the lines of magnetic force between and through the plates. 70

2. A field magnet having a passageway through the same, pole plates bridging such passageway and spaced apart to form an 80 interpolar gap, said plates having bores extending through the same in the direction of the lines of magnetic force between and through the plates, and means for passing the materials to be separated through said 85 passageway.

3. A field magnet having a passage way through the same adapted for the passage of the materials to be separated, pole plates bridging such passage way and spaced apart 90 to form an interpolar gap, said pole plates having bores extending through the same in the direction of the lines of magnetic force between and through the plates, one of said pole plates being removable. 95

4. A field magnet having a passageway through the same, pole plates bridging such passageway and spaced apart to form an interpolar gap, said pole plates having bores extending through the same in the direction 100 of the lines of magnetic force between and through the plates, means for passing the materials to be separated through said passageway, one of said pole plates being removable. 105

5. A field magnet having a passageway through the same adapted for passage of the materials to be separated, pole plates bridging such passageway and spaced apart to form an interpolar gap, said pole plates 110 having bores extending through the same in the direction of the lines of magnetic force through and between the plates, one of said pole plates being removable, and said field magnet having a wire chamber, magnet 115 wire wound in said chamber for magnetizing purposes, and means for excluding the magnetic particles from said chamber.

6. A field magnet having a passageway through the same adapted for the passage 120 of the materials to be separated, pole plates bridging such passage way and spaced apart to form an interpolar gap, said pole plates having bores extending through the same in the direction of the lines of magnetic force through and between the plates, means for passing the materials to be separated through said passageway, one of said 125 pole plates being removable, said field magnet having a wire chamber, magnet wire 130

wound in said chamber for magnetizing purposes, and means for excluding the magnetic particles from said chamber.

7. A magnetic separator, comprising a field magnet having a central passageway from end to end adapted for the passage of the materials to be separated, the wall of said passageway having within it a magnet wire chamber and provided with a uniform annular opening between said chamber and the central passageway to form a gap, pole plates held within said central passageway and forming a dam within the same, said plates being spaced apart to leave an inter-
- 15 polar gap between them, means for closing the gap of the field magnet against entry of the material into the wire chamber, a winding in said chamber, said pole plates having passageways extending through the same in the general longitudinal direction of the central passageway, whereby the non-magnetic material may be passed through the passageway and pole plates, and the magnetic material be caught by the pole plates.
- 20 8. A magnetic separator, comprising a field magnet having a central passageway from end to end adapted for the passage of the materials to be separated, the wall of said passageway having within it a magnet wire chamber and provided with a uniform annular opening between said chamber and the central passageway to form a gap, pole plates held within said central passageway and forming a dam within the same, said plates being spaced apart to leave an inter-
- 25 polar gap between them, means for closing the gap of the field magnet against entry of the material into the wire chamber, a winding in said chamber, said pole plates having passageways extending through the same in the general longitudinal direction of the central passageway, whereby the non-magnetic material may be passed through the passageway and pole plates, and the magnetic material be caught by the pole plates.
- 30 9. A magnetic separator comprising a field magnet with a central passageway from end to end adapted for the passage of the materials to be separated, the wall of which passageway has within it a magnet wire chamber and provided with an internal annular opening between said chamber and the central passageway to form a gap, pole plates held within said central passageway and forming a dam within the same, said plates being spaced apart to leave an inter-
- 35 polar gap between them, means for closing the gap of the field magnet against entry of the material into the wire chamber, a winding in said chamber, said pole plates having passageways extending through the same in the general longitudinal direction of the central passageway, whereby the non-magnetic material may be passed through the passageway and pole plates, and the magnetic material be caught by the pole plates, said pole plates having their opposing faces coniform.
- 40 10. A field magnet having a passageway through the same adapted for the passage of the materials to be separated, pole plates bridging such passageway and spaced apart to form an interpolar gap, said pole plates having bores extending through the same in the direction of the lines of magnetic force through and between said plates, the bores of the opposing plates being relatively staggeredly arranged.
- 45 11. A field magnet having a passage way through the same adapted for the passage of the materials to be separated, pole plates bridging such passageway and spaced apart to form an interpolar gap, said plates having bores extending through the same in the direction of the lines of magnetic force through and between the plates, the alternate ones of the bores in the plates being of larger diameter than the others, pins tightly fitted in the smaller bores of the plates, the pins of one plate projecting into the larger bores of the opposing plate.
- 50 12. In a magnetic separator, an iron clad electromagnet including a field magnet and an energizing winding therefor, said field magnet having a passage way extending axially through the same, pole plates within said passage way and having bores extending in the direction of the lines of force through and between said plates, through which bores the material to be separated is adapted to pass, said pole plates being spaced apart to form an interpolar gap.
- 55 13. In a magnetic separator, an iron clad electro-magnet including a field magnet and an energizing winding therefor, said field magnet having a passageway extending axially through the same, and adapted for the passage of the materials to be separated, a pole plate within said passageway and having bores extending through the same in the direction of the lines of force through said plate, through which bores the material to be separated is adapted to pass.

BYRON T. MOTTINGER.
